UNITED STATES PATENT OFFICE.

HERBERT H. CARSTENS, OF OAK PARK, ILLINOIS, ASSIGNOR TO H. CARSTENS MFG. CO., OF CHICAGO, ILLINOIS, A CORPORATION OF ILLINOIS.

VAGINAL DOUCHE.

Application filed January 15, 1926. Serial No. 81,367.

This invention relates to vaginal douches, and its principal object is to increase the efficiency of douches or syringes of this character and to simplify, strengthen and 5 otherwise improve the construction thereof. Another object is to provide means whereby the user may readily control the operation of certain vaginal wall expanding members of the device. Another object is to provide a douche or syringe that may be used 10 in connection with a rubber bulb or with a fountain syringe tank and its flexible tube. Another object is to provide a douche which may be easily cleaned and kept in a sanitary 15 and antiseptic condition. Other objects and advantages will appear in the course of this specification, and with all of said objects and advantages in view, this invention consists in the several novel features 20 of construction, arrangement and combination of parts, hereinafter fully set forth and claimed.

The invention is clearly illustrated in the accompanying drawing, in which:

25 Fig. 1 is a view, partly in side elevation and partly in central, longitudinal section, illustrating a simple embodiment of the present invention; Fig. 2 is a detail, horizontal section taken on the line 2—2 of Fig. 1; Fig. 30 3 is a detail side elevation of a certain finger actuating member forming part of the device; Fig. 4 is a detail, horizontal section, taken on the line 4—4 of Fig. 1; Fig. 5 is a detail, side elevation, partly broken 35 out, of a certain finger support forming part of the device, and Fig. 6 is a plan of a certain disc that forms part of the finger support seen in Fig. 5.

Referring to said drawing, which illustrates 40 a simple form of the present invention, the reference character 10 designates a spray tube or hollow member, which forms the main supporting element of the device. Said tube 10 is preferably provided with 45 perforations 11, adjacent one end and on said end is removably secured a perforated spray head 12. The spray head is preferably formed of vulcanized rubber or rubber composition, or other heat non-conducting material, whereby the possibility of injury to the user from excessive heat at this

place is eliminated. The spray head is preferably secured to the tube 10 by a threaded connection as shown, whereby it may be readily removed therefrom for the purpose 55 of cleaning the parts. Any foreign substances that might collect in and clog the perforations of the tube can be punched into the tube with a pin or other fine object and flushed out through the open end of the 60 tube.

On the other end of the tube 10, is secured a coupling 13, preferably having a threaded connection with the tube 10, and said coupling is formed with bulb and hose 65 attaching elements 14, 15, one of which 14, is designed for the attachment of a rubber bulb 16 or other bulb device, and the other 15, is designed for the attachment of the flexible tube of a fountain syringe. This 70 arrangement makes it possible to use the device with any of the common and well known sources of supply.

Rigidly secured on the tube 10, at a place intermediate its ends, is a finger supporting spider 17, which is of novel construction. Referring to Figs. 4, 5 and 6, the finger supporting spider 17 will be seen to comprise two oppositely disposed, substantially similar discs 18, 19, that may be struck up from sheet metal if desired, one of said discs having tongues 20 formed on its edge and adapted to be bent up and clinched over the edge of the other disc to rigidly fasten the two discs together. 80 Each disc has a central hole for the reception of the tube 10, and at equidistant places around the edge of each disc are formed pairs of parallel, spaced notches 21, in which the dilating fingers 22 are 90 pivotally secured by a wire ring 23 which is threaded through holes or bearing apertures in the dilating fingers. The ring 23 is contained in a narrow hollow space 24 formed by and between depressed portions 95 of the discs 18, 19. The ring 23 forms a common fulcrum for the several dilating fingers 22, and dispenses with the necessity of separate rivets or pivot pins for the several dilating fingers. In assembling these 100 parts the dilating fingers are strung upon the ring, the ring placed in the space left

between the two discs, and the tongues 20 of one disc bent up over the edge of the other disc and tightly forced down thereon, thus affording a very simple, yet effective pivotal connection between the dilating fingers and their supporting element. Moreover the edges of the slots 21 act as guides for the dilating fingers and prevent them from wabbling or tilting laterally, thus preserving them in parallel relation to the axis of the tube.

Grouped around the tube are the dilating fingers 22, which are preferably formed up from sheet metal by suitable dies, and are 15 U-shaped in cross section to afford great strength. Each dilating finger has a substantially straight portion 25 terminating in a slightly curved or bowed end part 26, and adjacent its fulcrum, the straight part is 20 formed with a notch 27 which is adapted for engagement with one end of an elastic, hollow, cone member 28, as will appear later. At the fulcrum place, the side flanges of 25 each dilating finger are widened slightly to accommodate the holes or bearing apertures for the fulcrum ring, and on the other side of the fulcrum, the metal of the dilating finger is struck inward or toward the tube 10, to form a reentrant part 30 from which the 30 terminal end part 31 stands at an angle to the main or straight part 25, and inclines outward or away from the tube, the terminal ends of the several fingers diverging from each other as is clearly shown in Fig. 35 1. Normally the bowed front ends 26 of the fingers are held in contact with the tube 10, but they are adapted to be spread apart by suitable means as will presently appear.

Improved means are provided for actuating the dilating fingers so as to spread their bowed ends apart, and said means will now be described.

Slidably mounted on the tube 10 is a finger actuating member 32, which, as shown, 45 comprises a finger engaging plate 33 having circumferentially arranged equidistant holes 34 formed therein, through which the terminal end portion 31 of the dilating fingers extend. The outer edges of the holes 34 engage with the outer sides of said terminal end portions 31 of the fingers, and act, when the plate 33 is moved in a direction away from the finger support 17, to draw the extreme ends of said terminal end parts together, 50 thereby spreading apart the other or operative ends of the dilating fingers, as is shown by the dotted lines in Fig. 1. Finger controlled means are provided for moving the finger actuating plate 33 axially along the 55 tube, and said means comprise a sleeve 36, rigidly secured to the plate 33, and slidably mounted on the tube. A sleeve extension 37 is threadedly secured to the sleeve 36 and has a finger ring 38 rigidly secured thereon, 60 which may be taken hold of by the thumb or

finger. Obviously, by drawing backward on the finger ring 38, the dilating fingers 22 are spread apart at their forward ends. By moving the finger ring 38 forward, or by releasing the ring and permitting the resilient small end of the cone to close, the fingers are returned to their closed position as shown by the full lines in Fig. 1.

A return flow collecting chamber is provided at the rear ends of the fingers, which comprises the hollow, flexible, yielding, elastic rubber cone member 28 above referred to, and a dished disc like plate 39 which is loosely mounted on the tube. The cone member 28 is formed with an internal bead or rim 40 on its small end which engages with the fingers, and said bead or rim 40 enters the notches 27 of said fingers. This arrangement effectively prevents the cone member from being displaced and at the same time the elastic cone member acts to close the fingers down on the tube when the finger actuating member is moved forward. The edge of the base portion of the cone member is reinforced by a grooved bead or rim 41 into which the edge of the disc like plate 39 fits. The cone member can be readily disconnected from the disc like plate, and its other end can be drawn out of the notches of the fingers, and the cone member can thereby be easily disconnected from the instrument for the purpose of cleaning the same.

To provide for a return flow, a nipple 42 for attachment to a flexible tube or hose (not shown) is provided on the disc like base plate 39, and a cap 43, removably secured on said nipple, may be provided to close the opening in said nipple whereby the chamber may be closed against escape of medicated liquid in case that is desired.

Among the advantages of this instrument is the ease with which it may be manipulated. The dilating fingers are under the control of the user and may be adjusted as desired, and easily held in any adjusted position. Another advantage is that it can be used with or without the return flow, and with a bulb or fountain syringe tube. The cone member 28 being made of flexible, yielding, soft rubber, it will effectively close the mouth of the vagina, thereby enabling the instrument to be used by a patient confined in bed.

More or less variation of the exact details of construction is possible without departing from the spirit of this invention; I desire, therefore, not to limit myself to the exact form of the construction shown and described, but intend, in the following claims, to point out all of the invention disclosed herein.

I claim as new, and desire to secure by Letters Patent:

1. In an instrument of the character de-

130

scribed, the combination with a spray tube, of a finger supporting spider stationarily secured thereon, dilating fingers grouped around said tube and fulcrumed on said spider to swing in planes parallel with the axis of said tube, each finger having a rearwardly and outwardly inclined, terminal end portion, a finger actuating member slidably mounted on said tube and having openings formed therein for the reception of said terminal end portion of the fingers, said member being movable lengthwise of the tube, and the outer edges of the openings therein being adapted, when said member is moved 10 in one direction lengthwise of the tube, to engage the inclined outer sides of said terminal end portions of the fingers and thereby spread apart the other ends of said fingers, a disc like base plate mounted on said spray tube beyond the terminal end portions of said dilating fingers, and a finger hold secured to said finger actuating member at a place beyond said disc like base plate.

2. In an instrument of the character described, the combination with a spray tube, of a finger supporting spider stationarily secured thereon, dilating fingers grouped around said tube and fulcrumed on said spider to swing in planes parallel with the axis of said tube, each finger having a rearwardly and outwardly inclined, terminal end portion on one side of its fulcrum, and a notch on the other side of its fulcrum, a finger actuating member formed with a plate slidably mounted on said tube and having openings formed therein for the reception of said terminal end portion of the fingers, said plate being movable lengthwise of the tube, and the outer edges of the openings therein being adapted, when said plate is moved in one direction lengthwise of the tube, to engage the inclined outer sides of said terminal end portions of the fingers and thereby spread apart the other ends of said fingers, a flexible, elastic, hollow cone member surrounding the rear end of said fingers and having a bead on the edge of its smaller end seated in the notches of the fingers, and having a grooved bead on the edge of its larger end, a disc like base plate loosely mounted on said tube with its edge engaged in said grooved bead, said finger actuating member being also formed with a sleeve secured to said plate and surrounding said tube, said sleeve extending beyond the free ends of said terminal end portions of the fingers, a disc like base plate mounted on said spray tube, with said sleeve extending through the base plate, 50 and a finger hold secured to said sleeve at a point beyond said base plate.

3. In an instrument of the character described, the combination with a spray tube, of a finger supporting spider stationarily secured thereon, dilating fingers grouped around said tube and fulcrumed on said spider to swing in planes parallel with the axis of said tube, each finger having a rearwardly and outwardly inclined, terminal end portion on one side of its fulcrum, and a notch on the other side of its fulcrum, a finger actuating plate slidably mounted on said tube and having openings formed therein for the reception of said terminal end portion of the fingers, said plate being movable

lengthwise of the tube, and the outer edges of the openings therein being adapted, when said plate is moved in one direction lengthwise of the tube, to engage the inclined outer sides of said terminal end portions of the fingers and thereby spread apart the other ends of said fingers, a flexible, hollow cone member surrounding the rear end of said fingers and having a bead on the edge of its smaller end seated in the notches of the fingers, and having a grooved bead on the edge of its larger end, a disc like base plate loosely mounted on said tube with its edge engaged in said grooved bead, and a sleeve secured to said finger actuating plate and extending out through said base plate, said sleeve having a finger ring secured to it.

4. In an instrument of the character described, the combination with a spray tube, of a finger supporting spider stationarily secured thereon, dilating fingers grouped around said tube and fulcrumed on said spider to swing in planes parallel with the axis of said tube, each finger having a rearwardly and outwardly inclined, terminal end portion on one side of its fulcrum, and a notch on the other side of its fulcrum, a finger actuating member formed with a plate slidably mounted on said tube and having openings formed therein for the reception of said terminal end portion of the fingers, said plate being movable lengthwise of the tube, and the outer edges of the openings therein being adapted, when said plate is moved in one direction lengthwise of the tube, to engage the inclined outer sides of said terminal end portions of the fingers and thereby spread apart the other ends of said fingers, a flexible, elastic, hollow cone member surrounding the rear end of said fingers and having a bead on the edge of its smaller end seated in the notches of the fingers, and having a grooved bead on the edge of its larger end, a disc like base plate loosely mounted on said tube with its edge engaged in said grooved bead, said finger actuating member being also formed with a sleeve secured to said finger actuating plate, and extending out through said base plate, a sleeve extension secured to the sleeve and forming a stop for said base plate, and a finger hold secured on said sleeve extension.

5. In an instrument of the character described, a dilating finger, U-shaped in cross section, throughout its length, and formed with bearing apertures, intermediate its ends, in the two sides of the U, there being a cone engaging notch on one side of said bearing apertures, and an angularly disposed terminal end portion on the other side of said bearing apertures, substantially and for the purpose set forth.

6. In an instrument of the character described, a finger supporting spider, comprising two oppositely disposed, substantially

similar discs, each formed with circumferentially arranged, equidistantly spaced pairs of notches, each pair of notches having a tang between them and each disc being formed with a circular depression, the depression in one disc facing the one in the other, and a ring contained in the space formed by said depressions and forming

multiple fulcrums, the one disc being formed with tongues bent over the edge of the other disc, and dilating fingers, each having flanged portions entering a pair of said notches and formed with bearing apertures for the reception of the ring. 10

HERBERT H. CARSTENS.
